UNITED STATES PATENT OFFICE.

LOUIS MARTAIN SARTAIN, OF PELHAM, TENNESSEE.

RAIL FASTENER.

Application filed December 21, 1922. Serial No. 608,268.

To all whom it may concern:

Be it known that I, LOUIS M. SARTAIN, a citizen of the United States, residing at Pelham, in the county of Grundy and State 5 of Tennessee, have invented a new and useful Rail Fastener, of which the following is a specification.

This invention relates to fasteners for railroad rails, one of its objects being to 10 provide a combined chair and clamp whereby when rails are properly positioned in engagement with the device they will be clamped tightly and held in proper relation with each other without the use of bolts, 15 fish plates, and the like.

Another object is to provide a structure of this character which can be applied readily to the ordinary wooden ties.

With the foregoing and other objects in 20 view which will appear as the description proceeds the invention consists of certain novel details of construction and combinations of parts which will be hereinafter more fully described and pointed out in the 25 claims, it being understood that various changes may be made in the construction and arrangement of parts without departing from the spirit of the invention as claimed.

30 In the accompanying drawings the preferred form of the invention has been shown.

In said drawings.

Figure 1 is a plan view of the rail fastener, portions of the joined rails being 35 broken away.

Figure 2 is a section on line 2—2 Figure 1.

Figure 3 is a section on line 3—3

Figure 1.

40 Figure 4 is a section on line 4—4

Figure 1.

Referring to the figures by characters of reference 1 designates an elongated base plate provided in the bottom face thereof 45 at each end, with a central longitudinal recess 2. Another recess 3 is formed in the top face of the plate 1 near each end and these recesses 3 communicate at their outer ends with the inner ends of the recesses 2. Additional recesses 4 are formed in the top 50 of the plate 1 close to and between the recesses 3.

Removably mounted on the plate 1 are 55 opposed clamping jaws 5 recessed, as at 6 to receive the base flanges *r* of the rails *R* to be joined. Thus the lower portions of

the jaws form seats 7 on which the rails are supported.

Extending outwardly from the jaws 5 are tongues 8 each having spaced projections 9 and 10 on the lower face thereof adapted to rest within the respective recesses 4 and 3. An ear 11 projects from the free end of the tongue at the bottom of projection 10 and is adapted to be seated in one of the bottom recesses 2. When the tongue 8 is properly seated on plate 1 the upper face of the tongue is slightly inclined upwardly toward jaw 5 as shown in Figure 2. Thus a holding band or ring 12 can be 70 slipped over plate 1 and tongue 8 and caused to frictionally engage them so as to bind them together.

Sockets 13 are provided in the gripping faces of the jaws 5 and pins 14, having 75 pointed ends, are adapted to be placed in holes *H* provided in the webs of the rails *R*.

In using this device the pins 14 are placed in the holes *H* so as to project beyond the webs of the rails. Plate 1 is then inserted 80 under the rails where they come together and while the tongues 8 are supported in inclined positions with the jaws 5 spaced apart the tongues 11 are inserted diagonally downwardly into the recesses 3 and 2 85 while the recesses 6 are positioned to receive the base flanges *r* of the rails. As soon as the parts have thus been assembled the rails are lowered toward the plate 1 and will thrust the tongues 8 downwardly until 90 the projections 9 and 10 are seated in the recesses 4 and 3. At the same time jaws 5 will move toward each other and clamp the webs of the rails, the pointed projecting ends of the pins 14 becoming seated in the sockets 13. Thereafter the bands or rings 12 can be placed in position and the parts 95 thus held securely. Plate 1 can be fastened to the usual wooden tie by means of spikes placed in openings 15 in the plate.

100 What is claimed is:

1. The combination with a base plate having recesses in the upper face thereof and recesses in the lower face communicating with the upper recesses, of opposed clamping jaws recessed to receive the base flanges of rails, said jaws having rail supporting portions, tongues extending from the jaws, projections on the tongues insertable downwardly into the recesses in the base plate, 110 and ears upon the projections insertable into the recesses in the top and bottom of the

plate and adapted to be seated in the bottom recesses.

2. The combination with a base plate having communicating recesses in the upper and lower faces thereof, of opposed rail clamping jaws having recesses for the reception of the base flanges of rails, tongues extending from the jaws, projections thereon adapted to be seated in the upper recesses, and ears on the projections insertable into the upper and lower recesses and adapted to be seated in the lower recesses.

3. The combination with a base plate having communicating recesses in the upper and lower faces thereof, of opposed rail clamping jaws having recesses for the reception of the base flanges of rails, tongues extending from the jaws, projections thereon adapted to be seated in the upper recesses, ears on the projections insertable into the upper and lower recesses and adapted

to be seated in the lower recesses, and bands detachably mounted on and extending around the plate and tongues for holding them assembled.

4. The combination with a base plate, of opposed rail clamping jaws having recesses for the reception of the base flanges of rails, there being sockets in the jaws, tongues projecting from the jaws, means on the tongues for interlocking engagement with the base plate, rails seated between the jaws, and pins extending transversely through the rails and having their ends projecting into the sockets in the jaws.

In testimony that I claim the foregoing as my own, I have hereto affixed my signature in the presence of two witnesses.

LOUIS MARTAIN SARTAIN.
